BAG CLOSURE

Gösta K. Odén, Nybro, Sweden

Application February 26, 1948, Serial No. 11,001
In Sweden December 7, 1945

3 Claims. (CL. 229—62)

1

This invention relates to envelopes or bags made from paper and similar material, and more particularly to the closing of such bags.

It is among the objects of this invention to provide a bag which can be closed easily and securely without auxiliary fastening elements, which can be opened readily without destroying the closure, and which is easy and inexpensive to manufacture.

In accordance with this invention the open end of the bag is provided with certain folds and slits so that the open end can be folded shut and its folded portions interlocked in such a way that the bag will remain closed and will prevent even granular material from escaping therefrom.

The preferred embodiment of the invention is illustrated in the accompanying drawings in which Fig. 1 is a side view of the unfolded bag with the folds indicated by broken lines; Fig. 2 is a similar view but with the open end of the bag folded down over the rest of it; and Fig. 3 is a view showing the bag completely closed.

Referring to Fig. 1 of the drawings, a flat rectangular envelope or bag, preferably made of fairly stiff paper, is open only along its top edge 1. The bag is provided with a fold 3 extending from the upper left hand corner diagonally across the upper portion of the bag to the opposite side 4. This forms a triangular portion bounded by edges 1 and 4 and fold 3. The angle α between this fold and the upper edge of the bag is less than the angle β between the fold and the side edge 2 of the bag, and therefore is less than 45° . The reason for this is that it is desirable, as will appear presently, that the upper edge 1 of the bag should be spaced from side edge 2 when the triangular portion above fold 3 is folded down over the rest of the bag as shown in Fig. 2. Suitable spacing of edges 1 and 2 is obtained when angle α is about 35° , although a few degrees more or less will not make any particular difference.

The bag is provided with a second fold 6 that extends from fold 3 diagonally across the bag to edge 2. To make the bag appear symmetrical when it is closed, the upper end of fold 6 preferably intersects fold 3 midway between the ends of the latter, while the lower end of fold 6 intersects edge 2 the same distance from the top of the bag as the lower end of fold 3. Extending from the upper end of fold 6 to upper edge 1 of the bag is a third fold 5 which faces in the opposite direction from the other two folds, but which is so positioned that when the triangular upper portion of the bag is folded down to the

2

position shown in Fig. 2, fold 5 will overlie fold 6. These overlying folds form the base of a pointed portion having converging sides formed by edge 2 and fold 3. As shown in Fig. 3, this pointed portion of the bag is bent on folds 5 and 6 over onto the lower part of the folded-down triangular portion of the bag.

This triangular portion's lower part, which is bounded by upper edge 1, side edge 4, and folds 3 and 5, has a slit 7 entirely through it in a position to permit the tip of the pointed portion of the bag to be inserted in it as shown in Fig. 3. The bag preferably has a slit 8 extending inward from edge 2 about midway between fold 6 and the upper end of the bag in the space between edges 1 and 2. By making this slit substantially parallel to fold 3, a tongue 9 (Fig. 3) is formed having parallel sides for a short distance. The tongue extends through slit 7, while slit 8 receives a portion of the lower part of the area containing slit 7 and helps to interlock the interengaged folded portions of the bag.

It will be seen that this bag is easy to manufacture because it is of conventional shape and is merely provided with three folds and two slits. The upper end of the bag can readily be folded and interlocked to hold the bag closed, and can be opened just as easily and then reclosed if desired. The outward pressure of the contents of the bag on the side walls of the bag can not loosen the closure, but, on the contrary, will press the overlapping folded areas more tightly together and thus lock the closure still more securely. This bag is particularly suitable for granular material because the sharp folds and the absence of slits in the body of the bag will keep the material from leaking out of it.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A bag of paper or the like having an open upper end and a first fold extending from one upper corner diagonally across the upper portion of the bag at an angle with its upper edge of less than 45° to form above the fold a triangular portion adapted to be folded down over the rest of the bag with said upper edge spaced inward from the adjacent side edge of the bag, the bag having a second fold extending from the central

portion of the first fold diagonally across the bag to said side edge, the bag having a third fold extending from the inner end of the second fold up to said upper edge in a position to overlie the second fold when said triangular portion is folded down, the portion of the bag above said overlying folds being pointed and adapted to be folded down over the lower part of said folded triangular portion, the bag being provided with a short slit extending inward from said side edge above the second fold, and said lower part of said triangular portion being provided with a slit substantially parallel to its lower edge and adapted to receive said folded pointed portion from its tip to the inner end of said short slit.

2. A bag of paper or the like having an open upper end and a first fold extending from one upper corner diagonally across the upper portion of the bag at an angle with its upper edge of less than 45° to form above the fold a triangular portion adapted to be folded down over the rest of the bag with said upper edge spaced inward from the adjacent side edge of the bag, the bag having a second fold extending from the central portion of the first fold diagonally across the bag to said side edge, the bag having a third fold extending from the inner end of the second fold up to said upper edge in a position to overlie the second fold when said triangular portion is folded down, the portion of the bag above said overlying folds being pointed and adapted to be folded down over the lower part of said folded triangular portion, the bag being provided with a short slit extending inward from said side edge above the second fold, said slit being substantially parallel to the first fold to form a tongue between them, and said lower part of said triangular portion being provided with a slit adapted to receive said tongue.

3. A bag of paper or the like having an open

upper end and a first fold extending from one upper corner diagonally across the upper portion of the bag at an angle with its upper edge of less than 45° to form above the fold a triangular portion adapted to be folded down over the rest of the bag with said upper edge spaced inward from the adjacent side edge of the bag, the bag having a second fold extending from the center of the first fold diagonally across the bag to intersect said side edge at about the same level as the lower end of the first fold, the bag having a third fold extending from the inner end of the second fold up to said upper edge in a position to overlie the second fold when said triangular portion is folded down, the portion of the bag above said overlying folds being pointed and adapted to be folded down over the lower part of said folded triangular portion, the bag being provided with a short slit extending inward from said side edge about midway between the second fold and the top of the bag, said slit being substantially parallel to the first fold to form a tongue between them, and said lower part of said triangular portion being provided with a slit substantially parallel to its lower edge and adapted to receive said tongue.
